UNITED STATES PATENT OFFICE.

WALTER S. ROBERTS, OF EDGEWOOD PARK, AND CHARLES H. HODGKINS, OF PITTSBURGH, PENNSYLVANIA, ASSIGNORS TO WESTINGHOUSE ELECTRIC AND MANUFACTURING COMPANY, A CORPORATION OF PENNSYLVANIA.

ANTIVIBRATION CATCH.

Application filed January 16, 1919. Serial No. 271,482.

To all whom it may concern:

Be it known that we, WALTER S. ROBERTS, a citizen of the United States, and a resident of Edgewood Park, in the county of Allegheny and State of Pennsylvania, and CHARLES H. HODGKINS, a subject of the King of Great Britain, and a resident of Pittsburgh, in the county of Allegheny and State of Pennsylvania, have invented a new and useful Improvement in Antivibration Catches, of which the following is a specification.

Our invention relates to damping means for oscillatory members and has particular relation to centrally biased switch members.

The object of our invention is to provide a mechanism for damping the oscillation of oscillatory members, to bring them to a stop with as little attendant vibratory movement as possible.

Our invention finds particular application in connection with controlling mechanisms, such as auto starters, the movable switch members of which are adapted to be held in closed position until released, whereupon the switch member, being centrally biased, oscillates backward and forward about the central position.

According to our invention, we mount, upon the centrally biased switch member, a projection which is adapted to engage a pivotally mounted catch member having a pair of gradually inclined surfaces separated by an abrupt surface. The projection engages first one of the gradually inclined surfaces, tilting the catch member about its pivotal point, then the second gradually inclined surface, tilting the catch member in the opposite direction and after a few impacts with the second surface and the abrupt surface, the switch member is brought to rest. A pin is mounted upon the frame to engage one of two projections of the catch member to limit its movement in the one or the other direction.

Our invention will be understood when described in connection with the accompanying drawings in which Fig. 1 is a fragmentary, sectional view of an auto starter embodying our invention; Fig. 2 is a view, partly in elevation and partly in section,

the plane of the section being taken at right angles to the section of Fig. 1; and Fig. 3 is an elevational view of our catch member.

Referring particularly to Figs. 1 and 2, the controlling mechanism comprises a casing having a stationary part 2 that is adapted to be secured to any suitable support and a part 3 for enclosing the switching mechanism. The part 3, which may constitute a tank for oil, in case the apparatus is employed in connection with high-voltage circuits, is removably secured to the stationary part 2 by means of latching mechanisms 4. The casing further comprises a removable cover member 5 which is loosely hinged to the member 3 by means of mutually engaging hook portions and is secured in position by a latching mechanism 6 that is located at the top of the casing.

The switching mechanism comprises two rows of stationary contact members 7 that are mounted upon, and insulated from, supporting bars 8. A corresponding number of pairs of oppositely disposed movable contact members 9 are mounted upon, and insulated from, a rock shaft 10. The respective contact members 9 are pivotally supported by pins 11, and the members of each pair are yieldingly retained in their relative positions, illustrated in Fig. 2, by means of springs 12.

The switching mechanism is operated by a handle lever 17 that is located outside the casing and is connected to the rock shaft 10. The operating lever 17 is normally retained in its inoperative position by a centering device 21 which comprises a stationary pin 22, two oppositely disposed curved arms 23 that are pivotally supported by the shaft 10 and that bear against the pin 22 when in their "off" positions, a spring 24 which resists the separation of the arms 23, and a pin 25 that is mounted upon an arm 26. The arm 26 is secured to the shaft 10 and extends upwardly therefrom.

Means are provided, also, for insuring that the operating lever shall be moved in one direction only from its inactive position. A pivotally mounted latching member 27 has a notch 28 in its bottom edge, one side

29 of which is inclined or beveled toward the pivotal support of such member so as to permit the pin 25 to move out of the notch. The other side of the notch is not inclined 5 or beveled but the material of the member is cut away at the side to decrease the depth of the notch at that side. This arrangement insures that the lever 17 shall be moved only in one direction from its inactive 10 position in which the pin 25 is seated in the notch 28. When the lever is operated to its starting position, the pin 25 is actuated to the right, as viewed in Fig. 2, to raise the member 27, whereupon the handle may be 15 actuated in the opposite direction to its running position if it is moved rapidly.

The upper end of the arm 26 is provided with a laterally projecting pin 30 which coacts with a latching mechanism 31 to retain the arm 26 and its connected mechanism in their running positions. The latching mechanism 31 comprises a pivotally mounted arm 32 that is provided with a hook 33 extending at right angles thereto. 25 The hook 33 is provided with a notch 34 and an inclined face 35 to coact with the pin 30. An electromagnet 36 retains the arm 32 in a vertical position when the pin 30 has been actuated into engagement with the notch 34. 30 The switching mechanism and the lever 17 are retained in their respective running positions by the electromagnet 36 except upon reduction of voltage to a predetermined low value, failure of voltage, opening of the circuit of the electromagnet coil, or other abnormal 35 conditions.

Upon the frame 2, at 60, we pivotally mount a catch member 61 having two inclined surfaces 62 and 63 and an intermediate 40 abrupt surface or shoulder 64. The arm 26 is provided with a pin or projection 65 to engage the surfaces 62, 63 and 64. The catch member 61 has also a recess 66 having two end shoulders 67 and 68 for engaging a 45 stop member 69 which is rigidly secured to the frame 2.

The operation is as follows: To start the motor, the lever 17 is first actuated to rock the shaft 10 in a clockwise direction as 50 viewed in Fig. 2. The switching mechanism is thereby actuated to the left, as viewed in Fig. 2, to effect engagement of the contact members 7 and 9 at the left. The arm 26 and the pin 25 move to the right, and the latch member 27 is raised by the pin to its 55 uppermost position. The projection 65 moves under the surface 63, the catch member 61 remaining in the illustrated position, with the surface 68 engaging the stop member 69. 60

When the motor has been accelerated sufficiently, the lever 17 is moved quickly in the opposite direction to its running position to effect a quick separation of the contact members 7 and 9 on the left and to effect 65

a correspondingly quick engagement of the coacting contact members at the right. A rapid movement of the mechanism is made necessary by reason of the fact that the latch member 27 engages the pin 25 and retains 70 the various parts in their respective active positions unless the pin 25 is moved across the notch 28 before the latch member 27 is actuated by gravity to engage the pin. During this movement, the projection 65 75 tilts the catch member 61 in the opposite direction, until the shoulder 67 engages the stop member 69. The catch member returns by gravity to its original, illustrated position but not until after the projection 65 has assumed a position to the left of the surface 62.

As the arm 26 and the pin 30 are moved to the running position, the latter engages the arm 32 to actuate the latter to its vertical position in which it is retained by the electromagnet 36. The hook member 33 is in such position that it is not engaged by the pin 30 during the movement above described. As the arm 32 is moved to its vertical position, 90 the hook member 33 rocks in a counter-clockwise direction about its point of pivotal support, and the pin 30 is thereby seated in the notch 34. The arm 26 and the various parts to which it is connected are retained 95 in their respective running positions under all normal conditions. The arm 32 is released, however, upon a failure of voltage or its reduction to a voltage of predetermined low value and the resultant de-energization of the magnet 36 or upon the opening 100 of the circuit of the latter by an overload relay.

Thereupon, the arm 26 will be returned automatically to its intermediate position and the arm 32 to its inactive position by the centering device 21. The tendency of the arm 26 to oscillate a number of times through its central, illustrated, position is overcome by our catch mechanism 61. Upon release of the arm 26, as above described, the projection 65 engages and moves over the surface 62, the shoulder 64 and into engagement with the surface 63. As the projection moves over the surface 62, the catch 110 member 61 is tilted in a clockwise direction but when it engages the surface 63, the catch 61 is tilted in a counter-clockwise direction until the shoulder 68 engages the stop member 69. The projection 65 may continue to oscillate between the surface 63 and the shoulder 64, its energy becoming spent by impact with these surfaces and the arm finally returning to its central, illustrated, inoperative position. The undesirable 115 numerous oscillatory movements of the arm 26 are thereby greatly reduced in number.

It will be understood that, although we have found the herein disclosed catch member to be of the best form and shape for our 130

purpose, our invention is not to be limited thereto but is commensurate, in breadth, with the appended claims.

We claim as our invention:

- 5 1. The combination with an oscillatory switch arm having a projection, of a pivotally mounted member that is freely movable within certain limits and that is adapted to be engaged by said projection to damp 10 the oscillations of said switch arm.
- 15 2. The combination with an oscillatory member, of a member having a pair of gradually inclined surfaces connected by an abrupt surface, said member being freely movable within certain limits and said surfaces being adapted to be engaged by said oscillatory member to damp its oscillations.
- 20 3. The combination with an oscillatory member, of means for damping the oscillations of said member, said means comprising a pivotally mounted member having two gradually inclined surfaces extending at different angles from a common point, a projection on said oscillatory member for engaging said surfaces and a stationary member for limiting the movements of said pivotally-mounted member.
- 25 4. The combination with an oscillatory member, of means for damping the oscillations

tions of said member, said means comprising a pivotally mounted member that is freely movable within certain limits and that is provided with two angularly spaced inclined surfaces and a projection on said oscillatory member for engaging said surfaces alternately.

5. In an auto starter, the combination with a centrally biased movable switch member having a projection, and means for maintaining said movable switch member in other than its central position, of means for damping the oscillations of said movable switch member when said maintaining means is rendered inoperative, said damping means comprising a member pivotally mounted upon said frame member and having a pair of gradually inclined surfaces connected by an abrupt surface, said surfaces being adapted to be engaged by said projection, and a member for limiting the movement of said pivotally mounted member.

In testimony whereof, we have hereunto subscribed our names this 31st day of Dec., 1918.

WALTER S. ROBERTS.
CHARLES H. HODGKINS.
